DESIGN FOR A DECANTER OR THE LIKE

Ewing S. Rixson, Greenwich, Conn., assignor to Robert H. Becker, Tuckahoe, N. Y.

Application July 24, 1946, Serial No. 131,877

Term of patent 14 years

(Cl. D36—2)

To all whom it may concern:

Be it known that I, Ewing S. Rixson, a citizen of the United States of America and a resident of Greenwich, in the county of Fairfield and State of Connecticut, have invented a new, original, and ornamental Design for a Decanter or the like, of which the following is a specification, reference being had to the accompanying drawing, forming part thereof, wherein:

Fig. 1 is a plan view of a decanter, showing my new design;

Fig. 2 is a side elevation of the same; and

Fig. 3 is an end elevation of the same.

I claim:

The ornamental design for a decanter or the like, as shown.

EWING S. RIXSON.
